UNITED STATES PATENT OFFICE.

JEFFERSON SCHELL AND ORIAN THOMAS PATERSON, OF OTTAWA, ONTARIO, CANADA.

ATTACHMENT FOR PAPER MACHINES.

Application filed January 27, 1926. Serial No. 84,230.

This invention relates to improvements in attachments for paper making machines and the objects of the invention are to provide a simply constructed and economical attachment for paper making machines whereby the rope carriers on the rolls are more securely retained in position.

Further objects are to provide a simply constructed attachment whereby the ropes or cords for taking the paper over the dryer will be effectively maintained from slipping over the end of the roll or dryer and breaking the ropes or cords.

With the foregoing and other objects in view the invention consists essentially of a substantially semicircular plate adapted to be rigidly attached to the frame of a paper making machine in that portion thereof where are provided the bearings for the paper carrying rolls. This plate is formed with a substantially horse-shoe sleeve on the inside designed to register with the outer periphery of the end of the dryer rolls so that when the retaining cords or canvas is inclined to slip over the ends down into the journal and on to the bearings they will be prevented from so doing by the sleeve of the attachment plate. In other words our improved attachment rigidly secured to the frame automatically closes the gap between the end of the dryer rolls and frame of the machine to act as a safety guide for the rope carriers.

Referring now to the drawings in which like characters of reference indicate corresponding parts in each Figure,

Figure 1 is a perspective view of a paper carrying roll with my improved attachment,

Figure 2 is a front view, partly in section showing the attachment secured to the frame and extending outwardly to cover the gap between the bearing carrying frame and the end of the paper carrying roll journalled in the bearing,

Figure 3 is a perspective detail of the attachment plate,

Figure 4 is an end view of rollers with ropes mounted thereon.

Referring now more particularly to the drawings in which a preferred example of our invention is illustrated 10 designates a paper carrying roll of an ordinary paper making machine provided with a spindle 11 journalled therein adapted to engage with a suitable bearing 12 in the frame 13 of the machine. Mounted on the frame and regis-

tering with the end of the roller 10 is our improved attachment rigidly mounted on the frame by bolts or the like 14 and comprising, as illustrated in Figure 3, a semi-circular plate 15, with suitable openings 16 therein to receive the securing member, a partially open sleeve or collar 17, the length and circumference of which may be varied in any suitable manner according to existing conditions.

In using our attachment the base or plate portion 15, as shown in Figure 2, is rigidly secured on the inside of the frame 13 above or beneath the bearing 12 for the spindle 11 journalled as at 18 in the paper carrying roll 10. In this position the sleeve or extension 17 will extend outwardly as at 19, Figure 2, to register with the outer periphery of the end 20 of the paper roll thus bridging the gap 21 between the end of the roll and the frame and so, preventing the ropes, cords or the like, used for holding the paper-carrier on the roll to slip off over the end and on to the bearings to get entangled with the spindle 11 and thus plug the machine causing considerable damage and often considerable expense.

As many changes could be made in the above construction and many apparently widely different embodiments of our invention, within the scope of the claims, constructed without departing from the spirit or scope thereof, it is intended that all matter contained in the present specification and accompanying drawings shall be interpreted in an illustrative and not in a limiting sense.

What we claim as our invention is:

1. In a paper making machine the combination with a frame having suitable bearings therein and a roll having a spindle journalled therein designed to be supported in said bearings, of a plate rigidly mounted on the frame and formed with an extension conforming to the contour of the roll and designed to bridge the space between the end of the roll and the frame.

2. In a device of the character described a plate or base of substantially semi-circular form and a collar formed on said plate of similar formation but of greater circumference than the plate.

In witness whereof we have hereunto set our hands.

JEFFERSON SCHELL.
ORIAN THOMAS PATERSON.
